DESIGN FOR A PAIR OF EYESHIELD CUPS FOR SUN BATHING

Orton William Lindgren, Jr., Reading, Pa., assignor to Willson Products, Inc., Reading, Pa., a corporation of Pennsylvania

Application September 4, 1946, Serial No. 133,051

Term of patent 14 years

(Cl. D57—1)

To all whom it may concern:

Be it known that I, Orton William Lindgren, Jr., a citizen of the United States, residing at Reading, in the county of Berks and State of Pennsylvania, have invented a new, original, and ornamental Design for a Pair of Eyeshield Cups for Sun Bathing, of which the following is a specification, reference being had to the accompanying drawing, forming part thereof.

Fig. 1 is a front view of a pair of eyeshield cups for sun bathing, showing my new design.

Fig. 2 is a corresponding plan view of the same.

Fig. 3 is a longitudinal sectional view taken on line 3—3 of Fig. 1; and

Fig. 4 is a cross-sectional view taken on line 4—4 of Fig. 1.

My design for a pair of eyeshield cups for sun bathing is characterized by the tubular integral projections on the nasal sides of the cups, all as illustrated.

I claim:

The ornamental design for a pair of eyeshield cups for sunbathing, as shown and described.

ORTON WILLIAM LINDGREN, JR.
